(57) **CLAIM**

The ornamental design for a handle of precision screwdriver, as shown and described.

DESCRIPTION

FIG. 1 is a perspective view of a handle of precision screwdriver showing my new design;

FIG. 2 is a front elevational view thereof; with the rear side being a mirror image of that shown;

FIG. 3 is a left side elevational view thereof; with the right side being a mirror image of that shown;

FIG. 4 is a top side elevational view thereof;

FIG. 5 is a bottom side elevational view thereof; and,

FIG. 6 is a perspective view thereof, wherein the broken line showing of the driver is for illustrative purposes only and forms no part of the claimed design.
